UNITED STATES PATENT OFFICE.

LEONARDO MARRA, OF PROVIDENCE, RHODE ISLAND.

LOCK.

Application filed October 20, 1924. Serial No. 744,708.

To all whom it may concern:

Be it known that I, LEONARDO MARRA, a citizen in the United States, residing at 22 Grape St., Providence, of the county of Providence and State of Rhode Island, have invented certain new and useful Improvements in Locks, of which the following is a specification.

My invention relates to locks, more particularly to permutation padlocks.

I am aware that permutation padlocks have been provided with a double set of combination locking elements to lock each end of the shackle and it is to this type of lock that my invention particularly relates. One object of my invention is to provide a stronger lock of this description than provided hitherto by providing two series of combination locking elements, each comprising a series of rotatable tumbler members having shaft portions contained respectively within hollow shaft portions of other tumbler members and enlarged locking portions radially notched grouped on each end of said shafts substantially contiguously to the enlarged locking portions of the other tumbler members and rotating dials therefor having permutation characters thereon grouped on the opposite end of said shafts substantially contiguously to the dials of the other tumbler members, said dials being visible and rotatably operable through side apertures in the casing to align said radial notches to form channels. It is obvious that this construction is one of great strength as the shaft portions continually bear against each other and the dials though independently rotatable bear against adjacent dials as do the enlarged locking portions. In addition therefore, to having both ends of the shackle securely locked, it is obvious that I have provided permutation locking elements of much greater strength than any hitherto employed in locks of this description.

I am aware that spring locks have been provided which automatically lock on the mere insertion of a slidable locking element. So far as I am aware however, the spring in these locks which resiliently bends to permit insertion of the slidable locking element has always been contained within the lock itself and so far as I am aware no-one has provided resiliently mounted locking means

in the slidable locking element to permit locking of the lock when the lock body portion itself is locked. I broadly claim this feature for use in any type of lock as it is much easier to mount the resilient bending elements in the slidable locking member than within the lock casing itself. It is obvious that practically no time is consumed in the mere insertion of the locking element, all that is necessary to lock a lock when this feature is employed. The use of a key, or the long time necessary to set a combination is eliminated. This is particularly true where a double combination lock is employed as in my preferred embodiment.

A further object of my invention is to provide a less easier broken lock than hitherto by completely enclosing the combination locking elements in compartments in a lock casing permitting the dials only to be visible and rotatably operable through side apertures in the casing. It is thus necessary to break the casing itself before attempting to break the combination locking elements. It is obvious that this gives more strength to the lock than where the combination locking elements are contained outside of the lock-body portion as in some former types.

These and such other objects of my invention as may hereinafter appear will be best understood from a description of an embodiment thereof such as the permutation padlock shown in the accompanying drawings.

Fig. 1 is a side elevation of an assembled padlock.

Fig. 2 is a central vertical section of my improved padlock, parts of the shackle being shown in elevation and with the shackle in locked position.

Fig. 3 is a plan view of my improved permutation padlock showing the shackle in unlocked position.

Fig. 4 is a cross sectional view taken along the line 4—4 of Fig. 2.

Fig. 5 is a cross sectional view taken along the line 5—5 in Fig. 1.

Fig. 6 is a central vertical sectional view similar to Fig. 2 with the combination locking elements set to form a channel to permit withdrawal of the shackle and with the shackle withdrawn.

Fig. 7 is a side elevation of the shackle.
Fig. 8 is a perspective view of a notched rack.

Fig. 9 is a perspective view of a base plate 5 mounted in channels cut in each arm of the shackle, having mounted thercon springs to bear against the racks shown in Fig. 8.

Fig. 10 is a reverse plan view of the longer shackle arm.

10 In the drawings, wherein like characters of reference indicate like parts throughout, 20 generally indicates my completed padlock. 22 indicates the lock casing or body portion which is conveniently divided into 15 compartments 24 and 26, conveniently separated by the wall 28. Each compartment is provided with a shackle arm receiving hole 30 and 31 respectively preferably made in the casing cover 32 and within said casing 20 22 and a side aperture 34.

I place within each compartment a set of combination locking elements which preferably comprise two series of rotatable tumbler members 38, each series being preferably identical in construction. Each tumbler member 38 has a shaft portion 40, an enlarged locking portion 42 at one end thereof and a dial 44 at the opposite end thereof. The shaft 40 of the internal tumbler member 38, is made longer and is contained within the hollow shaft 40' of the next adjacent tumbler member 38', the shaft 40' being correspondingly shorter and contained within the shorter hollow shaft 40'' of the next correspondingly shorter tumbler member 38'', the shaft 40''' being correspondingly shorter and contained within the correspondingly shorter hollow shaft 40''' of the external tumbler member 38''', the shafts being of such a length in relation to each other that the enlarged locking portions 42 of each shaft are revolvably located substantially contiguously to the enlarged locking portions of the next adjacent tumbler members 45 and the dials 44 are revolvably located substantially contiguously to the dials of the next adjacent tumbler members respectively. Each enlarged locking portion 42 preferably has its side tapered upwards as at 46 and is provided with the radial notch 48. Each dial 44 is provided around the periphery thereof with the desired permutation characters 50, the dials being so mounted within the lock casing 22 that the permutation characters 50 are visible and the dials 44 rotatably operable through the side apertures 34 in the respective compartments 24 and 26 of the lock casing 22. As stated the compartments 24 and 26 are provided with shackle arm receiving apertures 30 and 31, which apertures extend substantially the length of the tumbler clusters 38, the aperture 31 being slightly longer than the aperture 30 for the reasons to be described.

65 Having now described the novel features

of my lock casing and locking elements contained therein I will describe in detail the shackle I employ, as it embodies a feature which I believe is new in spring locks of any description. The shackle 52 is provided with the arms 54 and 56 as usual. Instead of inwardly notching the arms 54 and 56, as usual, I cut the channels 58 transversely of said arms. Each channel 58 tapers as at 60 at each end thereof towards 75 the inner edge of each shackle arm. I place within said tapering channels 58 the movable racks 62 provided on one side thereof with the notched teeth 64 and having each end thereof tapering as at 66 toward the 80 side having the notched teeth 64. I mount the springs 68 in the channels 58, to bear against the base 70 of the racks 64. It is obvious that the springs 68 will tend to press the racks 64 outwardly, until they abut 85 the tapered ends 60 of the channel 58 thereby preventing further forward movement thereof, but that the notched racks 64 may be pushed inwardly in said channels 58 until the teeth 64 no longer project beyond the 90 inner sides of the shackle arms 54 and 56. While any means may be employed for mounting the springs 68 within the channels 58, I preferably mount said springs 68 on the base plates 72, which base plates are 95 preferably of a longer length than the channels 58 and are attached to the outer side of the shackle arms exterior of said channels 58 by means of the screws 74. As explained, the locking portions 42 of the tumbler members 38 taper upwardly thereby providing an outwardly tapered inclined surface 46 on each periphery thereof, terminating in the outwardly extending edges 45 at the lower ends of the enlarged locking portions 100 42. The teeth 64 in the rack 62 are preferably of sawtooth construction having the straight sides 76 and the inclined sides 78. The racks 62 are so mounted on the channels 58 that the straight sides 76 of the 105 teeth are upwards. It is obvious that with this construction the shackle arms 54 and 56 may be inserted in the shackle arm receiving holes 30 and 31 and as the shackle arms 54 and 56 sink in said holes the tapered peripheries 46 of the enlarged locking portions 42 will bear against the inclined sides 78 of the teeth 64 of the racks 62 thereby pressing the racks 62 inwardly within the channels 58 and permitting deep insertion 110 of said shackle arms 54 and 56 in their respective holes 30 and 31 to lock the lock no matter what position on the periphery of the enlarged locking portions the notches 48 may be. When the shackle 52 is suitably inserted within the lock-casing 22 it is obvious that the edges 45 of the peripheries of the enlarged locking portions 42 will bear 115 against the flat sides 76 of the rack teeth 64, pushing downwardly and not inwardly on 120

- said rack teeth, and that the racks 62 cannot be pushed into the channels 58 when the shackle is being pulled outwards to permit unlocking of the lock. It is obvious 5 however, that to withdraw the shackle 52 from the lock and thus unlock the lock it is necessary to align the radial notches 48 in the enlarged locking portions 42 to form a channel 80, (Fig. 6), which alignment may 10 be accomplished by turning the dials 44 to the desired predetermined permutation settings. It is obvious that the principle of having a lug or other member resiliently mounted in the slideable locking member of 15 a lock to permit insertion of said locking member within the lock even when a suitable locking lug or other member in a lock is moved to locked position so as to retain the slideable locking member in locked position 20 is a new principle in all types of locks.
- The shackle arm 56 is preferably made slightly longer than the shackle arm 64 and is provided with the locking pin 82 transversely mounted therein. It is obvious that 25 with this construction the shackle 52 when raised to unlocked position, will have the arm 54 outside the shackle arm receiving hole 30, but that the arm 56 will be retained to the casing by the pin 82 and that it is 30 also obvious that when thus raised to locked position, the shackle arm 54 may be revolved around the arm 56 as a pivot to permit withdrawal of the chain, link or other locking device used from the shackle 52, (Fig. 3).
- The cover 32 may be conveniently secured to 35 the lock casing 22 by the screw 33, the heads of which after insertion thereof may be suitably enlarged to permit removal of the cover therefrom.
- It is obvious that I have provided a very 40 compact permutation padlock, having separate combination locking elements adapted to securely lock both arms of a shackle thereby doubly locking the padlock and that by 45 providing means resiliently mounted in a slideable locking element I have provided a spring lock of an entirely different type than any hitherto devised.
- It is understood that my invention is not 50 limited to the specific embodiments shown and that various deviations may be made therefrom without departing from the spirit and scope of the appended claims.
- What I claim as new and desire to secure 55 as Letters Patent is:
1. A permutation padlock, comprising a lock casing having two compartments, each having a shackle arm receiving aperture and an aperture in the side thereof, a series of 60 rotatable tumbler members contained within each compartment having shaft portions contained respectively within the hollow shaft portions of other tumbler members, enlarged locking portions radially notched 65 grouped on one end of said shafts substantially contiguously to the enlarged locking portions of the other tumbler members and rotating dials therefor having permutation characters thereon grouped on the opposite end of said shafts substantially contiguously 70 to the dials of the other tumber members, said dials being visible and rotatably operable through the side apertures in the casing to align said radial notches to form channels 75 and a shackle member having two arms, each arm having a notched rack mounted on springs in a channel therein whereby said shackle may be inserted within said lock when the locking portions of said tumbler members are in any position to retain the 80 shackle to the lock and whereby on rotation of said dials to the predetermined setting, the radial notches of each series of tumbler members 85 may be aligned to form a channel to permit withdrawal of said shackle arms. 85
2. A permutation padlock, comprising a lock casing having two compartments, each having a shackle arm receiving aperture and an aperture in the side thereof, a series of 90 rotatable tumbler members contained within each compartment having shaft portions contained respectively within the hollow shaft portions of other tumbler members, enlarged locking portions radially notched 95 grouped on one end of said shafts substantially contiguously to the enlarged locking portions of the other tumbler members and rotating dials therefor having permutation characters thereon grouped on the opposite end of said shafts substantially contiguously 100 to the dials of the other tumbler members, said dials being visible and rotatably operable through the side apertures in the casing to align said radial notches to form channels 105 and a shackle member having two arms, each arm having lock engaging means resiliently mounted therein whereby said shackle may be inserted within said lock when the locking portions of said tumbler members 110 are in any position to retain the shackle to the lock and whereby on rotation of said dials to the predetermined setting, the radial notches of each series of tumbler members may be aligned to form a channel to permit withdrawal of said shackle arms. 110
- In testimony whereof I affix my signature. 115

LEONARDO MARRA.
